Des. 194,734
Patented Feb. 26, 1963

194,734

PORABLE WATER SOFTENER

James B. Mobley, 5643 Hazeltine Ave., Van Nuys, Calif.,
and Harold Nemer, 11448 Kingsland St., Los Angeles, Calif.

Filed Apr. 26, 1962, Ser. No. 69,863

Term of patent 14 years

(Cl. D91—1)

FIGURE 1 is a perspective view of a portable water softener showing our new design;

FIGURE 2 is an elevational view illustrating the side opposite that shown in FIGURE 1; and

FIGURE 3 is a top plan view of the same.

The portions fragmentarily shown in broken lines in FIGURES 1 and 3 are included for illustrative purposes only.

We claim:

The ornamental design for a portable water softener, substantially as shown and described.
